Primary Examiner—Stella M Reid*Assistant Examiner*—Mark A Goodwin(74) *Attorney, Agent, or Firm*—Perman & Green, LLP(57) **CLAIM**

The ornamental design for a cabinet handle, as shown and described.

DESCRIPTION

FIG. 1 is a perspective view of cabinet handle showing our new design;

FIG. 2 is a top view thereof;

FIG. 3 is a front view thereof; and,

FIG. 4 is side view thereof.

The broken lines showing the upper and lower portion of the cabinet handle are included for the purpose of illustrating portions of the cabinet handle and form no part of the claimed design.
